METHOD OF MAKING SHOES.

1,413,588.

Specification of Letters Patent. Patented Apr. 25, 1922.

Application filed March 5, 1918. Serial No. 220,488.

To all whom it may concern:

Be it known that I, BERNHARDT JORGENSEN, a subject of the King of Denmark, residing at Beverly, in the county of Essex and State of Massachusetts, have invented certain Improvements in Methods of Making Shoes, of which the following description, in connection with the accompanying drawings, is a specification, like reference characters on the drawings indicating like parts in the several figures.

This invention relates to methods of making shoes, and in one aspect relates more particularly to methods of manufacture in which the side-lasting operation is performed prior to the toe-lasting operation as, for example, in the manufacture of a certain type of shoe in which the upper consists of felt material, the term "side-lasting" being used herein with particular reference to the operation of conforming the upper to the forepart of the last at the rear of the toe portion, which may include more or less lateral stretching of the upper. In many of its aspects, however, the invention is not confined to methods involving this particular sequence of operations nor restricted to the manufacture of felt shoes.

In the manufacture of felt shoes of the type above referred to it is the usual practice to cut the upper of sufficient size to permit its lower marginal portion to be extended inward at the bottom of the shoe in such manner as to serve to a greater or less extent as an insole, and before the shoe is mounted on a last to stitch the bottom edges of the opposite side portions of the upper either directly together or to an insertion of similar material extending for a portion at least of the distance lengthwise of the shoe. The upper is then dampened and a last is inserted to stretch and form the material in lasted shape. In accordance with the usual practice and for the best results the bottom edges of the material in the toe portion of the shoe are left free and unsecured until after the last has been inserted, after which this portion of the shoe, while damp, is shaped by a toe lasting operation.

50 The operation of lasting the toe of such a shoe must be performed with due regard to the peculiar conditions resulting from the

preceding steps in the manufacture of the shoe, as well as to the character of the material of which the shoe is made. At the rear 55 of the toe portion where the shoe is already side-lasting the upper is stretched across the last, or laterally, to its final shape, and in a less degree the upper at the sides and over the top of the toe is likewise stretched laterally by reason of its connection to the stretched portion. At the toe end of the last, however, the upper is in a substantially un-stretched condition, and in lasting the toe it is therefore desirable to pull this portion of the upper to some extent over the last. This operation, however, and also the operation of laying the margin of the upper over the bottom of the last, must be so performed as to avoid distorting the previously side-lasting 60 portion of the shoe and also to avoid crowding any portion of the unsecured margin back over the side-lasting portion on the margin of the last bottom. It has been the practice heretofore to grip different portions of 70 the unsecured margin of the upper in succession with hand pincers and to pull each portion so gripped and draw it inward over the bottom of the last and then to drive a tack to secure it in lasted position. In order to 75 flatten the stock down upon the margin of the last at the toe, a plurality of blows are then delivered on the stock with a hammer. After the stock has dried and set in permanent shape the tacks are removed, the up-standing edges of the upper at the toe end are 80 trimmed off, and an outsole is stitched to the shoe.

The toe lasting operation performed in the manner above described is not only slow but is frequently productive of unsatisfactory results. It is very difficult, in pulling over and securing different portions of the stock in succession, and particularly in pulling the portions at the sides of the toe, to effect uniform lasting and to avoid, on the one hand, distorting the previously side-lasting portions back of the toe and, on the other hand, producing one or more pleats or folds in the stock so pronounced as to extend out near the edge 95 of the shoe in the portion to which the outsole is to be stitched. Such a fold in the margin near the edge of the shoe is likely to be cut when the upstanding edge of the upper is 100

trimmed off, with a consequent weakening of the portion of the shoe to which the outsole is to be attached. The strength of the felt material, moreover, frequently varies in different portions, and for this reason and in view of the damped condition of the material there is danger of tearing it by too hard a pull or of rupturing it by the blows delivered over the margin of the last bottom for flattening the margin.

One important object of this invention, among others, is to provide an improvement in methods of making shoes involving particularly the operation of shaping the toe portion of the shoe to the last, to the end that the difficulties heretofore encountered in the manufacture of shoes of the kind above referred to, for example, may be avoided and uniform lasting of the toe portion of the shoe may be effected in an expeditious and otherwise satisfactory manner. In one aspect the invention provides for wiping inward uniformly over the margin of the bottom of a last different portions of the margin of the upper at the toe of the shoe with respectively different pressures, these pressures, in the case of a shoe previously side-lasting, being proportioned as between the end and the sides of the toe with reference to the different degrees of stretching required in different portions of the stock and with a view to avoiding displacement of the previously lasted portion back of the toe. It is also contemplated, in one aspect of the method, that the wiping action on the stock shall be effected with a substantial component of wiping pressure directed laterally of the shoe at the end as well as at the corners and sides of the toe, thus causing the inner free edge of the margin to be gathered within a comparatively small area and in the case of a previously side-lasting shoe insuring against crowding the material at the sides of the toe portion back over the portion previously side-lasting. Preferably the wiping pressures and the directions of the wipe on different portions of the stock are so determined as to produce a uniformly flat margin round the toe while leaving the inner free edges of the stock at the sides of the toe upstanding and so disposed, as the result of a substantially direct wipe inward from the side edges of the last, as to extend in directions lengthwise of the shoe, the wiping being so effected, moreover, as to cause the remainder of the free inner edge of the upper at the toe end to be gathered substantially between the upstanding edges at the sides. In the case of a shoe having an insertion secured by seams to the edges of the upper, these upstanding side edges of the stock will preferably be so located as to extend substantially from the ends of the seams toward the toe end of the shoe. While the upper may be secured tem-

porarily in lasted position in different ways, it is preferred to secure it by fastenings such as tacks driven respectively at the outer sides of the upstanding side edges of the stock and by one or more additional tacks 70 driven in front of the intermediate gathered portion of the edge.

In a further aspect the invention contemplates pulling the upper at the toe end of the last prior to the final lasting of the 75 margin. In the illustrative practice of the method it is preferred to grip a portion of the margin at the toe end of comparatively small extent widthwise of the shoe and by pulling in this location to stretch lengthwise 80 of the shoe the toe portion of the upper, and in some degree also, in the case of a previously side-lasting shoe, the portion already stretched transversely of the last over the top of the forepart, leaving the portions at 85 the sides of the toe substantially free from lateral pulling tension, and then to draw the gripped portion of the upper inward over the bottom of the last. It is contemplated that in a shoe of the kind referred to 90 the pull thus effected will be all that conditions will require, since the portions of the upper at the corners and the sides of the toe, by reason of their connection to the tensioned portion at the end of the toe and the 95 portion previously side-lasting, will be so stretched as to require no local pulling, the subsequent overwiping of the stock being depended upon to tension the upper in some degree at the sides and corners of the toe 100 sufficiently to render the condition of the stock uniform. An important advantage in thus manipulating the stock in such manner as to eliminate any necessity for pulling it at the sides of the toe is that the danger of 105 displacing the side-lasting portion by such pulling action is avoided. The drawing of the gripped portion of the upper inward from the end of the toe as above described contributes beneficially to the subsequent 110 gathering of the intermediate portion of the free edge of the upper between the upstanding edges at the sides of the toe, since the material, particularly if damped, tends to retain its overdrawn position even after it 115 is released and thus to project backwardly between portions subsequently wiped inward from the sides. Such release of the gripped portion is effected preferably before any overwiping of the margin of the upper takes 120 place, since it is desirable that all portions of the margin have a normal degree of tension at the time of the overwiping action, both in order to insure uniformity of effect at all portions of the margin and also to 125 avoid undue strain upon any portion of the stock such as might be produced by a combined pulling and wiping action. Before the margin of the upper is released it is preferable to engage the upper for holding 130

it in its tensioned condition, and this object may be conveniently attained by pressing against the upper on the toe end face of the last.

5 In order to assist in explaining the nature of the invention there is shown in the accompanying drawings certain apparatus which may be used with advantage in practising the novel method, but it should be understood that the invention is not dependent upon the use of the apparatus shown or of any particular apparatus. It should also be understood that although the invention is herein described as adapted particularly for 10 use in the manufacture of a specific kind of shoe, the invention in many of its aspects is not necessarily restricted to the manufacture of the particular type of shoe described.

The drawings show, by way of example, 20 portions of a machine devised for carrying out the novel method of this invention, this machine being more fully shown and described and the novel features thereof claimed in a co-pending application, Serial 25 No. 220,489, filed contemporaneously herewith. Only such portions of the machine as it is necessary to refer to for an understanding of the method are illustrated in the drawings, and the construction of the parts shown 30 need be described herein only very briefly.

In the drawings,

Fig. 1 shows in side elevation a toe gripper and toe lasting wipers and tackers in their relation to a felt shoe of the kind hereinbefore referred to, and illustrates the step of gripping and pulling on the margin of the upper at the toe end to stretch a portion of the upper lengthwise and over the toe of the last,

40 Fig. 2 shows the gripper still in engagement with the upper but pulling it inward or backward over the bottom of the last, and shows also a member pressing against the upper on the toe end face of the last in position to hold the upper tensioned after the gripper has released the margin,

Fig. 3 shows the gripper released and the wipers closed up into substantial conformity to the lateral contour of the toe end of the shoe before they have begun to wipe the stock over the bottom of the last,

Fig. 4 shows the wipers fully closed, and

Fig. 5 shows the shoe with its toe lasted and secured by the method of this invention.

55 In the manufacture of a felt shoe of the type illustrated the upper, as above explained, is cut of sufficient size to permit portions to be turned inward at the bottom of the shoe, the inturned portions of the 60 completed shoe lying between the outsole and the wearer's foot and serving practically, to a greater or less extent, as an insole for the shoe. The inturned portions may extend as far as the longitudinal median 65 line of the bottom of the shoe, and in such

case the lower edges of the upper are stitched directly together as far forwardly as a point near the toe end of the shoe before the shoe is mounted on a last. Alternatively, as in the shoe shown in the drawings, 70 the upper may be cut smaller, particularly at the forepart, and a piece *a* of material similar to that of the upper inserted between and stitched to the edges of the upper to secure them together. An advantage of this 75 course is that the inserted piece, which finally is to be covered by the sole, may be of inferior material and thus may contribute to economy in the manufacture of the shoe. If the shoe is made in this manner the upper is 80 cut large enough to permit the seams *b* by which it is attached to the inserted piece to extend along the bottom of the last at sufficient distances from the lateral edges of the 85 last to afford a marginal portion *c* of the superior upper stock for the attachment of the outsole, and the inserted piece and the 90 seams terminate at a distance from the toe end of the shoe, as does the middle seam if the shoe is made in the other manner described, thus leaving the margin of the upper stock free and unsecured at the toe.

95 After the parts have been cut and stitched as above described, the shoe is dampened in order to temper the stock and render it readily moldable, and the shoe is then mounted on a last. The parts are so proportioned as to size that the insertion of the last serves to stretch the stock to such an extent as to cause all portions, except the unsecured toe 100 part, to be conformed closely to the last. It will be evident that with the last thus inserted the connected portions of the stock back of the toe part are stretched to their final shape transversely of the last and a 105 considerable degree of longitudinal stretching also is effected by the last, while portions in the toe part adjacent to the stretched portion are also stretched to some extent by reason of their connection to the stretched portion.

110 In accordance with the present method, as practised with the aid of the mechanism herein shown, the shoe, while the stock is still damp or after it has been again dampened at the toe end, is presented in engagement with a bottom rest 2 and a comparatively small portion of the margin of the upper at the toe end is gripped and pulled by means of a toe gripper 4. This serves to 115 stretch a portion of the upper which by reason of its remoteness from the portion previously stretched by the insertion of the last has up to this time remained in substantially its original condition as to tension. While it is within the province of the invention to pull more of the margin of the upper, extending for example to the corners of the toe end of the last, if desired, it is contemplated that these portions, as well as 120 125 130

the portions at the sides of the toe, by reason of their connection to the portion pulled by the gripper 4 and to the previously side-lasted portion, will usually require no local pulling. It will be evident, moreover, that the pull at the toe end serves also to produce an additional lengthwise stretching of the previously stretched portion at the top of the forepart. When the gripper 4 is operated 10 the bottom rest 2 is rocked downward by a cam 8 to assist the operation of the gripper and a heel rest 10 is moved up into supporting relation to the heel end of the shoe, and while the parts are thus positioned side arms 15 12 are swung inward from opposite sides of the shoe to bring shoe supporting and holding devices into engagement with the shoe at the sides and under the forepart.

The next step or steps in the method, as 20 preferably practised, are illustrated by Fig. 2 where the front arm 14 (Fig. 1) carrying lasting devices has started to swing toward the shoe about an axis above the shoe not shown in the drawings. Simultaneously the 25 toe gripper 4 is swung inward to draw the pulled margin of the upper at the toe end backward over the bottom of the last. The arm 14 carries wiper plates 16 which are pivoted at 18 and are connected by links 20 30 (Fig. 4) to levers 22 pivotally mounted on the wiper support, the inner ends of these levers being engaged by a slide 24 and operatively connected to springs 26 which tend to position the parts with the wipers fully 35 open. Carried by the slide 24 is an abutment 28, and in the position of the parts illustrated by Fig. 2 this abutment has been carried into engagement with the upper on the toe end face of the last. During the continued inward movement of the arm 14 the abutment 28 and the slide 24 remain stationary by reason of the engagement of the abutment with the shoe, and as the arm continues its movement the levers 22 are caused 40 45 to fulcrum on the slide and to swing the wipers 16 inwardly, meanwhile further tensioning the springs 26 and causing the abutment 28 to bear with increasing pressure against the shoe in such manner as to hold the upper in its tensioned condition irrespective of continued engagement of the gripper jaws with the margin.

By the time the wipers 16 have been advanced and closed into substantial conformity to the lateral contour of the shoe, as shown in Fig. 3, but preferably before they have begun to wipe the stock over the bottom of the last, the gripper 4 is caused to release its hold upon the stock by the tripping of a latch device 30. At this time the gripper has advanced far enough over the bottom of the last to pull the intermediate part of the margin of the upper back at a comparatively small angle to the bottom of the last. The abutment 28 is now in

position to prevent the tension of the upper from relaxing, and the wipers begin to close uniformly over the last bottom at the sides and the end of the toe portion of the shoe, wiping the margin of the upper inward. 70 Since the wipers have closed substantially into conformity to the contour of the shoe before their wiping action begins, they now become immediately effective to wipe the upper inward at the sides of the shoe at the 75 time that they also begin to advance over the toe end of the shoe, the effectiveness of the wipers in directions laterally of the shoe as compared with their wiping action lengthwise of the shoe being further insured by 80 positioning the pivot 18 at a considerable distance back of the wiping edges, as shown, as well as by the character of the operating connections for the wipers. The tendency of the wipers consequently is to gather all 85 portions of the margin of the upper inward laterally of the toe portion of the shoe. Since the intermediate portion of the margin of the upper has already been drawn backward by the gripper into a position which, 90 by reason of its damped condition, it tends to retain after the gripper is released, the wipers serve to wipe the upper from the sides of the toe part inward toward this intermediate portion and finally form pleats 95 or folds in the free edge of the upper presenting lateral upstanding portions *d* (Fig. 5) positioned substantially in front of the ends of the seams *b* while other portions of the free edge of the upper, including one or 100 more rearwardly extending folds *e*, are gathered between these lateral upstanding portions. The wipers are closed laterally inward substantially as far as the seams *b* but preferably not far enough to effect any 105 considerable pressure against these seams such as to displace the previously stretched portions of the stock.

It is also an object of the invention, as hereinbefore explained, to wipe inward at 110 the sides of the toe part with less pressure than at the end and corners of the toe, both for the reason that close to the previously stretched and secured portion back of the toe less stretching is necessary in the toe lasting 115 operation and also because of the need for avoiding displacement of the previously stretched portion. This object is attained by beveling the shoe engaging faces of the wipers at their end portions, as indicated 120 at 32, thus causing these portions to press more lightly upon the stock. The swinging movement of the arm 14, and the means for positioning the shoe including the adjustable shoe engaging finger 34 on the bottom rest 125 2, may also be utilized in co-operation to contribute to the same result by causing the ends of the wipers to incline upward slightly from the shoe bottom in their final position.

Fig. 4 illustrates the final closed position of the wipers. When the wipers have arrived at this position tacks *f* are driven to hold the margin in place. Preferably two of these tacks are located at the outer sides of the lateral upstanding folds *d*, substantially in line with the seams *b*, with one or more additional tacks in front of the intermediate gathered portion. The tacks are driven by tackers 36, the two side tackers being mounted for swinging movement with the wipers and connected to the wipers by studs 38 to cause them to be swung inward by the movement of the wipers for driving the tacks in the correct relation to the wiping edges.

After the shoe has been lasted as above explained, it is permitted to dry in order to set the material in permanent shape. The toe tacks are then removed, the upstanding edge of the upper at the toe is trimmed off, and an outsole is stitched to the shoe.

It will be evident that by the method herein described the upper is stretched and shaped to the last at the toe uniformly at all portions of the toe and the margin of the upper is molded down flat upon the bottom of the last to produce a smooth surface for the reception of the sole without any pronounced folds which might be accidentally cut at the time when the upstanding gathered edge is trimmed off, and it will also be evident that the operation produces a lasted toe portion which merges smoothly with the previously side-lasted portion back of the toe. The uniformity of the work also results in the requirement of fewer tacks for holding the margin in lasted position than have been required heretofore, and this not only saves tacks but also avoids the rapid wear of the last which is the well known result of driving repeatedly a large number of tacks in this location.

It will be understood from the foregoing description that in some aspects this invention provides a method of particular utility in the manufacture of shoes of felt material irrespective of whether the side lasting is performed prior to the toe lasting, while in other aspects the utility of the invention is not in any way dependent upon the character of the material of which the shoe may be made.

Having explained the nature of the invention and set forth fully how it may be practised, what I claim as new and desire to secure by Letters Patent of the United States is:

1. That improvement in methods of making shoes which consists in side-lasting the shoe, subsequently wiping the unsecured margin of the upper inward over the bottom of the last at the end and the sides of the toe with less effective pressure upon the stock at the sides of the toe adjacent to the

previously side-lasted portion than at the end of the toe, and then securing the toe portion of the upper in lasted position.

2. That improvement in methods of making shoes which consists in side-lasting the shoe, and then wiping the margin of the upper round the toe inward over the bottom of the last with less effective wiping pressure upon the stock at the sides of the toe adjacent to the previously side-lasted portion than at the end of the toe and with wiping pressures directed at all points laterally of the shoe.

3. That improvement in methods of making shoes which consists in securing together the bottom edges of the opposite side portions of an upper along the forepart at the rear of the toe, then inserting a last in the upper to stretch laterally and conform to the last the secured portions at the rear of the toe, engaging the upper at the end of the toe and stretching it lengthwise while maintaining the portions at the sides of the toe substantially free from lateral pull to prevent distorting the previously stretched portion at the rear of the toe, and then wiping the margin of the upper inwardly over the bottom of the last at the end and the sides of the toe and fastening it.

4. The improvement in methods of making shoes which consists in side-lasting the shoe, subsequently wiping the margin of the upper inward over the bottom of the last at the opposite sides of the toe substantially simultaneously to form at the inner portion of said margin upstanding edges extending from the previously side-lasted portion of the upper in a direction toward the toe end of the shoe, and wiping the margin of the upper at the toe end of the shoe over the bottom of the last and gathering its inner edge substantially between said upstanding side edges.

5. That improvement in methods of making shoes which consists in side-lasting the shoe, subsequently wiping the margin of the upper inward over the bottom of the last at the end and the sides of the toe with pressures so directed as to form upstanding folds in the inner edge of said margin directed forwardly at the sides of the shoe from said previously side-lasted portion and one or more folds between said side folds directed rearwardly, and then driving fastenings substantially at the outer sides of said side folds and one or more fastenings in front of the folds to secure the upper in lasted position.

6. That improvement in methods of making shoes which consists in wiping the margin of the upper inward over the bottom of the last round the toe with pressures so directed as to form at the inner edge of said margin at the sides of the toe upstanding folds directed forwardly toward the toe end

- of the shoe and to gather the intermediate portion of the margin substantially between said upstanding folds at the sides, and then securing the toe portion of the upper in 5 lasted position.
7. That improvement in methods of making shoes which consists in side-lasting the shoe, wiping the margin of the upper inward over the bottom of the last at the sides 10 of the toe to form at the inner edge of the margin folds extending forwardly toward the toe end without overlapping the previously side-lasted portion back of the toe, and wiping the margin of the upper at the toe 15 end over the bottom of the last with a greater degree of effective pressure on the stock than that applied at the sides and with wiping pressures directed at all points laterally of the shoe to gather the intermediate portion of the free edge of the upper substantially between said folds.
8. That improvement in methods of making shoes which consists in side-lasting the shoe, subsequently gripping at the toe end 20 of the last a portion of the upper and pulling it while leaving free the margin of the upper at the sides of the toe, and then wiping the margin of the upper uniformly inward over the bottom of the last round the toe as far back as the previously side-lasted portion by pressures so differentiated between the end and the sides of the toe as to 25 wipe the stock in uniformly while avoiding displacement of the previously lasted portion 30 of the upper.
9. That improvement in methods of making shoes which consists in side-lasting the shoe, pulling the upper at the toe end of the last to stretch it lengthwise of the shoe, and 35 then wiping the margin of the upper inward over the bottom of the last at the end and the sides of the toe with less wiping pressure at the sides than at the end of the toe.
10. That improvement in methods of 40 making shoes which consists in side-lasting the shoe, subsequently gripping at the toe end of the last a portion of the upper of comparatively narrow extent widthwise of the shoe and pulling the upper, and then 45 while retaining the upper at the end of the last in tensioned condition wiping the margin of the upper inward over the bottom of the last at the end and the sides of the toe as far back as the side-lasted portion with 50 wiping pressures directed at all points laterally of the shoe.
11. That improvement in methods of 55 making shoes which consists in gripping at the toe end of the last a portion of the upper of comparatively narrow extent widthwise of the shoe and pulling the upper, pressing against the upper on the end face of the last to retain it in tensioned condition and releasing the pull on the upper, and then while 60 retaining the upper at the end of the last
- in tensioned condition wiping the margin of the upper inward over the bottom of the last round the toe with wiping pressures directed at all points laterally of the shoe.
12. That improvement in methods of making shoes which consists in side-lasting the shoe, gripping the margin of the upper at the toe end of the last and pulling it, engaging the upper on the lateral surface of the last to hold it in its tensioned condition and 70 releasing the margin, and then wiping the margin of the upper inward over the bottom of the last with less wiping pressure at the sides of the toe adjacent to the previously lasted portion than at the end of the toe. 75
13. That improvement in methods of making shoes which consists in side-lasting the shoe, gripping and pulling at the toe end of the last a portion of the margin of the upper of comparatively narrow extent widthwise of the shoe to stretch the upper, drawing said gripped portion of the upper inward over the bottom of the last, wiping over the bottom of the last the margin of the upper at the sides and the corners of 80 the toe and said overdrawn portion at the end of the toe to form in the edge of the upper folds extending forwardly at the sides of said overdrawn portion and one or more folds between said side folds extending rearwardly, and securing the toe portion of the upper in lasted position. 85
14. That improvement in methods of making shoes which consists in gripping and pulling a portion of the margin of the upper 90 at the toe end of the last to stretch the upper, pressing the upper against the toe end face of the last to hold it in stretched condition, drawing the margin of the upper at the toe end of the last inward over the bottom of the last and then releasing it, and after the margin of the upper has been released at the toe 95 wiping the margin uniformly inward from the edge of the last bottom at the end and sides of the toe by pressures directed at all points laterally of the shoe and securing it in lasted position. 100
15. That improvement in methods of making felt shoes which consists in side-lasting the shoe, subsequently gripping and pulling 105 a portion of the margin of the upper at the toe end of the last while in dampened condition to stretch the upper, engaging the upper to hold it in stretched condition and releasing the margin, and then wiping the 110 margin of the upper uniformly inward over the bottom of the last round the toe as far back as the previously side-lasted portion with pressures so directed as to gather the free edge of the end portion of the upper 115 substantially between portions wiped in from the sides of the toe. 120
16. That improvement in methods of making felt shoes which consists in dampening the upper, gripping the margin of the upper 125

at the toe end of the last and pulling it to stretch the upper, drawing the pulled margin inward over the bottom of the last, pressing against the upper on the toe end face of the 5 last to hold it in stretched condition and then releasing the margin, and after the margin is released wiping it inward over the bottom of the last uniformly round the toe by pressures directed at all points laterally of the 10 shoe and with less effective wiping pressure at the sides of the toe than at the end of the toe.

17. That improvement in methods of making felt shoes which consists in securing the 15 opposite side portions of the upper to a bottom piece by seams positioned to extend along the bottom of the shoe in locations spaced inwardly from the side edges of the last, then wiping the margin of the upper 20 inwardly over the bottom of the last at the opposite sides of the toe substantially simultaneously to form at the inner portion of said margin upstanding edges extending lengthwise of the shoe substantially in front 25 of the ends of said seams, gathering other portions of the unsecured margin at the toe between said upstanding side edges, and securing the toe portion of the upper in lasted position.

30 18. That improvement in methods of making felt shoes which consists in securing the opposite side portions of the upper to a bottom piece by seams positioned to extend along the bottom of the shoe in locations 35 spaced inwardly from the side edges of the last, then gripping and pulling the upper over the toe of the last and inwardly over the bottom of the last by engagement with a portion of the margin of the upper at the 40 end of the toe, wiping the unsecured portion of the upper inward over the bottom of the last uniformly round the toe to gather the unsecured edge of the upper within an area substantially between the ends of said 45 seams, and securing the toe portion of the upper in lasted position.

19. That improvement in methods of making felt shoes which consists in dampening the upper, gripping the margin of the upper 50 at the toe end of the last and pulling it to stretch the upper, drawing the pulled margin inward over the bottom of the last, pressing against the upper on the toe end face of the last to hold it in stretched condition and then releasing the margin, and after the margin is released wiping it from the edge of the last bottom inward uniformly round the toe.

55 20. That improvement in methods of mak-

ing shoes which consists in lasting an upper 60 into conformity to the forepart of a last at the rear of the toe, thereafter pulling the upper over the end of the toe of the last while leaving the portions at the sides of the toe substantially free from lateral pulling tension and then working the margin of the upper inwardly over the bottom of the last uniformly round the end and along the sides of the toe and fastening it in 65 lasted position.

70 21. That improvement in methods of making shoes which consists in stretching an upper laterally and lasting it over the forepart of a last at the rear of the toe, thereafter pulling the upper at the end of the toe 75 only to stretch it lengthwise and draw it over the end face of the last without distorting the previously lasted portion at the rear of the toe, and then wiping the margin of the upper over the bottom of the last 80 round the end and along the sides of the toe to gather it in front of the previously lasted portion at the rear of the toe and fastening it in lasted position.

85 22. That improvement in methods of making shoes which consists in side-lasting the shoe at the rear of the toe, thereafter gripping the margin of the upper and pulling it at the end of the toe, pressing against the toe end face of the shoe to hold the upper 90 and then releasing the margin, and gathering and wiping the upper inwardly round the end and along the sides of the toe and fastening it.

95 23. That improvement in methods of making shoes which consists in side-lasting the shoe at the rear of the toe, thereafter gripping the upper at the end of the toe only and pulling it first heightwise of the last 100 and then rearwardly over the bottom of the last, wiping the margin of the upper inward uniformly round the end and along the sides of the toe to gather it in front of the previously lasted portion, and then fastening the toe portion of the upper in lasted 105 position.

24. That improvement in methods of making shoes which consists in side-lasting the shoe at the rear of the toe, thereafter pulling the upper over the toe end of the last, 110 and then gathering and wiping the margin of the upper inwardly over the bottom of the last round the end and along the sides of the toe with wiping pressures directed at all points laterally of the shoe.

115 In testimony whereof I have signed my name to this specification.

BERNHARDT JORGENSEN.
